UNITED STATES PATENT OFFICE.

FRANK J. UNGER, OF AKRON, OHIO, ASSIGNOR TO THE STARDANT RUBBER COMPANY, OF KENMORE, OHIO, A CORPORATION OF OHIO.

DIPPING-FORM-CLEANING APPARATUS.

Application filed October 23, 1926. Serial No. 143,680.

- This invention relates to apparatus for cleaning dipping forms such as used for making dipped rubber goods as, for example, finger cots, nipples, gloves, etc.
- 5 The general purpose of the invention is to provide an improved apparatus for effectively cleaning dipping forms. In particular the invention has for its object the provision of means for feeding form boards carrying rotatable forms along a path, means for rotating the forms as the boards are moved along the path and means operable against the forms (during their travel and while rotating) progressively from one 10 end to the other thereof for effectively cleaning the same.
- The foregoing and other objects are obtained by the construction shown in the accompanying drawings and described below.
- 20 It is to be understood that the invention is not limited to the specific form thereof shown and described.
- Of the accompanying drawings,
- 25 Figure 1 is a side elevation of a portion of an apparatus illustrating the invention applied thereto;
- Figure 2 is a plan thereof;
- Figure 3 is a section on line 3—3 of Figure 1;
- 30 Figure 4 is a section on line 4—4 of Figure 1; and
- Figure 5 is a section on line 5—5 of Figure 1.
- Referring to the drawings, the numeral 35 10 designates a slide comprising spaced members 11, 11 along which form boards 12, 12, having two rows of rotatable forms 13, 13 depending therefrom, may be moved by a chain 15 having dogs 16, 16 thereon for 40 engaging boards 12. Chain 15 may be driven by a sprocket 17 driven by a motor 18 through a reduction 19 in any suitable manner. It is to be understood that chain 15 is arranged for moving the boards 12 along slide 10 past other mechanism (not 45 shown) prior to the cleaning apparatus depicted in the drawings. In order to rotate the forms 13 as they pass through the cleaning apparatus, plates 20, 20 are provided on each side of slide 10 and yieldingly urged inwardly by springs 21, 21 into frictional engagement with rollers 22, 22 secured to the forms 13.
- The cleaning devices comprise horizontal 50 brushes 23, 23, 24, 24 and 25, 25 arranged
- on opposite sides of the path of the forms through the apparatus for progressively brushing downwardly from the bottoms of the forms; inclined brushes 26, 26 on opposite sides of the path of the forms for brushing the forms one or more times progressively downwardly from their bottoms to their tops; and a horizontal brush 27 arranged beneath the path of the forms to brush the top ends thereof. 60
- For driving of the various brushes, a motor 35 may be employed which is arranged to drive a shaft 34 having thereon reversely arranged bevel gears 33, 33 meshing with bevel gears 32, 32 on shafts 37, 37 so as to 70 drive said shafts in opposite directions. Shafts 37 are in turn geared to shafts 31 at 36, 36 and shafts 31 are arranged to drive brushes 23, 24 and 25 by sprockets 30, 30 driving chains 29, 29 which are trained over 75 sprockets 28, 28 connected to brushes 23, 24 and 25. Bevel gears 38 on shafts 37 mesh with bevel gears 39 to drive brushes 26. A sprocket 42 on shaft 34 drives a chain 41 trained over a sprocket 40 to drive brush 27. 80
- In operation the boards 12 are continuously advanced through the apparatus and after certain other operations, e. g. bead-forming, vulcanizing, stripping, etc., arrive at the cleaning apparatus in which the 85 forms are rotated as they travel by means of friction plates 20. In the cleaning apparatus the forms of each row are first subjected to brushing downwardly a short distance progressively from their bottom (upper) edges by the brushes 23, 24 and 25, adjacent each row. The forms are then subjected to a series of brushing actions progressively downwardly from their bottoms (upper portions) to their tops (lower portions) by brushes 26. Finally the forms are subjected to a brushing of their top ends (lower ends) by brush 27 and pass from the machine ready for reuse in dipping articles. 90
- It will appear that, due to rotation of the forms, only one brush operating on one side of each form is required for performing a cleaning operation on each form and by arranging the brushes in pairs with the forms traveling between them two rows of 95 forms may be effectively cleaned at the same time. The machine, accordingly, is adapted for effective cleaning of forms in a rapid and economical manner. 100
- Modifications of the invention may be re- 110

sorted to without departing from the spirit thereof or the scope of the appended claims.

What is claimed is:

1. Apparatus for cleaning dipping forms, comprising a slide including spaced members adapted to support form boards slid-
able on said members and having two rows
of forms rotatably mounted thereon and de-
pending between the members and rollers
connected to the forms, yielding friction
plates mounted on the members and urged
against the rollers of each row of forms,
means for sliding the boards along the mem-
bers, and means for progressively brushing
the forms downwardly from their bottoms
to their tops, said means including a series
of horizontal, rotatable brushes on each side
of the slide having progressively lower axes,
a series of inclined, rotatable brushes on each
side of the slide for brushing each row of
forms downwardly from their bottoms to
their tops, a rotatable brush extending
transversely beneath the slide for brushing
the top ends of both rows of the forms and
means for rotating the brushes on the sides
of the slide so as to brush the forms down-
wardly. 70
2. Apparatus for cleaning dipping forms comprising a slide including spaced members adapted to support form boards slid-
able on said members and having two rows
of forms rotatably mounted thereon and de-
pending between the members and rollers
connected to the forms, yielding friction
plates mounted on the members and urged
against the rollers of each row of forms,
means for sliding the boards along the mem-
bers, and means for progressively brushing
the forms downwardly from their bottoms to
their tops, said means including a series of
inclined, rotatable brushes on each side of
the slide for brushing each row of forms 80
downwardly from their bottoms to their
tops and means for rotating the brushes on
the sides of the slide so as to brush the
forms downwardly. 85
3. Apparatus for cleaning dipping forms, 90
comprising a slide including spaced members
adapted to support form boards slidable on
said members and having two rows of forms
rotatably mounted thereon and depending
between the members and rollers connected
to the forms, yielding friction plates mounted
on the members and urged against the
rollers of each row of forms, means for slid-
ing the boards along the members, and
means for progressively brushing the forms
downwardly from their bottoms to their
tops, said means including a series of hori-
zontal, rotatable brushes on each side of the
slide having progressively lower axes, a ro-
tatable brush extending transversely be-
neath the slide for brushing the top ends of
both rows of the forms, and means for ro-
tating the brushes on the sides of the slide
so as to brush the forms downwardly. 100
4. Apparatus for cleaning dipping forms, 95
comprising a slide including spaced members
adapted to support form boards slidable on
said members and having two rows of forms
rotatably mounted thereon and depending
between the members and rollers connected
to the forms, yielding friction plates mounted
on the members and urged against the
rollers of each row of forms, means for slid-
ing the boards along the members, and
means for progressively brushing the forms
downwardly from their bottoms to their
tops, said means including a series of
inclined, rotatable brushes on each side of
the slide for brushing each row of forms 110
downwardly from their bottoms to their
tops and means for rotating the brushes on
the sides of the slide so as to brush the
forms downwardly. 115
5. Apparatus for cleaning dipping forms, 120
comprising a slide including spaced members
adapted to support form boards slidable on
said members and having two rows of forms
rotatably mounted thereon and depending
between the members and rollers connected
to the forms, yielding friction plates mounted
on the members and urged against the
rollers of each row of forms, means for slid-
ing the boards along the members, and
means for progressively brushing the forms
downwardly from their bottoms to their
tops, said means including a series of
horizontal, rotatable brushes on each side of
the slide having progressively lower axes
and means for rotating the brushes on the
sides of the slide so as to brush the forms
downwardly. 125
6. Apparatus for cleaning dipping forms, 130
comprising a slide including spaced members
adapted to support form boards slidable on
said members and having two rows of forms
rotatably mounted thereon and depending
between the members and rollers connected
to the forms, yielding friction plates mounted
on the members and urged against the
rollers of each row of forms, means for slid-
ing the boards along the members, and
means for progressively brushing the forms
downwardly from their bottoms to their
tops, said means including a series of
inclined, rotatable brushes on each side of
the slide having progressively lower axes
and means for rotating the brushes on the
sides of the slide so as to brush the forms
downwardly. 135
7. Apparatus for cleaning dipping forms,
comprising a slide including spaced mem-
bers adapted to support form boards slid-

able on said members and having two rows of forms rotatably mounted thereon and depending between the members and rollers connected to the forms, yielding friction plates mounted on the members and urged against the rollers of each row of forms, means for sliding the boards along the members, means for progressively brushing the forms downwardly from their bottoms to their tops, a rotatable brush extending transversely beneath the slide for brushing the top ends of the forms and means for rotating the brushes on the sides of the slide so as to brush the forms downwardly.

8. Apparatus for cleaning dipping forms, comprising a slide including spaced members adapted to support form boards slid- able on said members and having forms ro- 20 tatably mounted thereon and depending be- 25 tween the members, means for sliding the boards along the members, means for rotat- ing the forms on the boards as the latter are slid along the members, and means for 30 progressively brushing the forms down- 35 wardly from their bottoms to their tops, said means including a series of horizontal, ro- 40 tatable brushes having progressively lower axes, a series of inclined, rotatable brushes for brushing the forms downwardly from 45 their bottoms to their tops, a rotatable brush extending transversely beneath the slide for 50 brushing the top ends of the forms and means for rotating the horizontal and in- 55 clined brushes so as to brush the forms down- 60 wardly.

9. Apparatus for cleaning dipping forms, comprising a slide including spaced mem- 40 bers adapted to support form boards slid- able on said members and having forms ro- 45 tatably mounted thereon and depending be- 50 tween the members, means for sliding the boards along the members, means for ro- 55 tating the forms on the boards as the latter are slid along the members, and means for 60 progressively brushing the forms down- 65 wardly from their bottoms to their tops, said means including a series of horizontal, ro- 70 tatable brushes having progressively lower axes, a series of inclined, rotatable brushes for brushing the forms downwardly from 75 their bottoms to their tops and means for 80 rotating the brushes so as to brush the forms downwardly.

55 10. Apparatus for cleaning dipping forms, comprising a slide including spaced mem- 55 bers adapted to support form boards slid- able on said members and having forms ro- 60 tatably mounted thereon and depending be- 65 tween the members, means for sliding the boards along the members, means for ro- 70 tating the forms on the boards as the latter are slid along the members, and means for 75 progressively brushing the forms downwardly 80 from their bottoms to their tops, said means

including a series of inclined, rotatable brushes for brushing the forms downwardly from their bottoms to their tops, a rotatable brush extending transversely beneath the slide for brushing the top ends of the forms and means for rotating the inclined brushes so as to brush the forms downwardly.

11. Apparatus for cleaning dipping forms, comprising a slide including spaced mem- 75 bers adapted to support form boards slid- able on said members and having forms ro- 80 tatably mounted thereon and depending be- 85 tween the members, means for sliding the boards along the members, means for ro- 90 tating the forms on the boards as the latter are slid along the members, and means for 95 progressively brushing the forms down- 100 wardly from their bottoms to their tops, said means including a series of inclined, ro- 105 tatable brushes for brushing the forms down- 110 wardly from their bottoms to their tops and means for rotating the brushes so as to brush the forms downwardly.

12. Apparatus for cleaning dipping forms, comprising a slide including spaced mem- 60 bers adapted to support form boards slid- able on said members and having forms ro- 65 tatably mounted thereon and depending be- 70 tween the members, means for sliding the boards along the members, means for ro- 75 tating the forms on the boards as the latter are slid along the members, and means for 80 progressively brushing the forms down- 85 wardly from their bottoms to their tops, said means including a series of horizontal, ro- 90 tatable brushes having progressively lower axes, a rotatable brush extending trans- 95 versely beneath the slide for brushing the top ends of the forms and means for ro- 100 tating the series of horizontal brushes so as 105 to brush the forms downwardly.

13. Apparatus for cleaning dipping forms, comprising a slide including spaced mem- 110 bers adapted to support form boards slid- able on said members and having forms ro- 115 tatably mounted thereon and depending be- 120 tween the members, means for sliding the boards along the members, means for ro- 125 tating the forms on the boards as the latter are slid along the members, and means for 130 progressively brushing the forms down- 135 wardly from their bottoms to their tops, said means including a series of horizontal, ro- 140 tatable brushes having progressively lower axes and means for rotating the brushes so as to brush the forms downwardly.

14. Apparatus for cleaning dipping forms, comprising a slide including spaced mem- 125 bers adapted to support form boards slid- able on said members and having forms ro- 130 tatably mounted thereon and depending be- 135 tween the members, means for sliding the boards along the members, means for ro- 140 tating the forms on the boards as the latter are slid along the members, rotatable means

- for progressively brushing the forms downwardly from their bottoms to their tops, a rotatable brush extending transversely beneath the slide for brushing the top ends 5 of the forms, and means for rotating the rotatable means so as to brush the forms downwardly.
15. Apparatus for cleaning dipping forms, comprising a slide including spaced members adapted to support form boards slide- 10 able on said members and having two rows of forms rotatably mounted thereon and de- pending between the members and rollers connected to the forms, yielding friction plates mounted on the members and urged 15 against the rollers of each row of forms, means for sliding the boards along the mem- bers, and means for progressively brushing the forms downwardly from their bottoms 20 to their tops.
16. Apparatus for cleaning dipping forms, comprising a slide including spaced members adapted to support form boards slide- 25 able on said members and having forms ro- tatably mounted thereon and depending be- tween the members, means for sliding the boards along the members, means for ro- tating the forms on the boards as the latter 30 are slid along the members, and means for progressively brushing the forms down- wardly from their bottoms to their tops.
17. Apparatus of the class described, comprising means for rotatably mounting a series of forms in inverted relationship, means for moving the forms along a path, 35 means to rotate the forms as they move along said path, and means for cleaning the forms including one or more brushes alongside of said path operable to brush downwardly progressively from the bottom 40 to the top of the forms and a brush beneath the path for brushing the tops of the forms.
18. Apparatus of the class described, comprising means for rotatably mounting a se- 45 ries of forms in inverted relationship, means for moving the forms along a path, means to rotate the forms as they move along said path, and means for cleaning the forms in- cluding one or more brushes alongside of said path operable to brush downwardly 50 progressively from the bottom to the top of the forms.
19. Apparatus of the class described, comprising means for mounting a series of forms in inverted relationship, means for moving 55 the forms along a path, and means for clean- ing the forms including one or more brushes alongside of said path operable to brush downwardly progressively from the bottom to the top of the forms and a brush beneath 60 the path for brushing the tops of the forms.

FRANK J. UNGER.
